UNITED STATES PATENT OFFICE.

WILLIAM A. HELLER, OF MUSKEGON, MICHIGAN, ASSIGNOR TO JENNIE G. HELLER AND HAROLD W. HELLER, OF MUSKEGON, MICHIGAN.

TROLLEY HARP AND WHEEL.

SPECIFICATION forming part of Letters Patent No. 692,851, dated February 11, 1902.

Application filed October 29, 1901. Serial No. 80,434. (No model.)

To all whom it may concern:

Be it known that I, WILLIAM A. HELLER, a citizen of the United States, residing at Muskegon, in the county of Muskegon and State of Michigan, have invented certain new and useful Improvements in Trolley Harps and Wheels; and I do hereby declare the following to be a full, clear, and exact description of the invention, such as will enable others skilled in the art to which it appertains to make and use the same.

My invention consists in the novel features of construction hereinafter described, reference being had to the accompanying drawings, which illustrate one form in which I have contemplated embodying my invention, and said invention is fully disclosed in the following description and claims.

Figure 1 represents a top plan view of my improved trolley harp and wheel. Fig. 2 is a vertical cross-section taken on line 22, Fig. 3. Fig. 3 is a side elevation of my device. Fig. 4 is a plan and sectional view of the brush.

The object of my invention is to provide an improved trolley harp and wheel adapted for use upon high-speed roads, whereby the said harp and wheel are less apt to leave the wire and the current is more effectively collected from the trolley-wheel and conveyed to the pole.

In carrying out the above objects I cast a trolley-harp A with the usual rope-attaching ear 3, an internally-screw-threaded shank or stock B, and a wheel-carrying portion in the form of a triangle with angular portions 4 thereof extending upward in the direction of the wire, as clearly shown in Fig. 3. The triangular portion above mentioned is provided with a suitable opening for a grooved trolley-wheel 1, which is mounted on a shaft 5 in the lower part thereof.

The inner faces 11 11 of the angular portions 4 on each side of the trolley-wheel are curved inward from front to back, as shown in Fig. 1, for permitting the trolley-wheel to properly follow the wire around curves and switches and are inclined inward from the top of the harp to a point adjacent to the uppermost part of the periphery of the wheel 1 for centering the wire upon the same. The

harp is further provided on the inside with recesses 8 8, adjacent to the shaft 5, adapted to receive brushes 7 7.

The trolley-wheel 1 is provided with an oil-reservoir 13 and a removable bushing 6, having openings 12 therein communicating with said reservoir. The hub of said wheel on both sides thereof is formed with concave portions 9 9, adapted to conform to the configuration of the brushes 7 7. The periphery of this wheel 1 is preferably provided with a shallow groove 2, the wire being kept in the same by means of the inclined faces 11 11 of the harp.

The brushes 7 7 are made of spring brass or copper and are substantially of the form shown in Fig. 4, having an opening 10, through which the shaft 5 of the trolley-wheel passes.

When the parts are assembled, it will be observed that the brushes 7 7 will lie in the recesses 8 8 in the position shown in dotted lines, Fig. 1, and the curved central portion of the said brushes will engage the concave portions of the hub of the wheel. Thus the brushes provide for a frictional contact between the wheel and the harp.

It will be noted that the inner faces 11 11 of the angular portions 4 4 of the harp approach each other most nearly at points above the axis of the trolley-wheel and recede from each other, both forward and in rear of said points, thus facilitating the passage of the trolley-wheel around curves and over switches.

What I claim, and desire to secure by Letters Patent, is—

1. The combination with a trolley-harp provided with upwardly-extending angular portions, the inner faces of said portions approaching each other most nearly at points directly above the axis of the trolley-wheel and receding from each other forward and in rear of said points to facilitate rounding curves, and a trolley-wheel mounted in said harp, substantially as described.

2. The combination with a trolley-harp provided with upwardly-extending angular portions, the inner faces of said portions approaching each other most nearly at points directly above the axis of the trolley-wheel and receding from each other forward and in rear

of said points to facilitate rounding curves, said faces being also inclined upwardly and outwardly and a trolley-wheel mounted in said harp below said faces, substantially as described.

3. The combination with a trolley-harp having recesses in the inner lateral faces thereof, of a trolley-wheel mounted in said harp and provided with a hub having concave lateral faces and brushes located in said recesses and engaging said concave portions of said hub, substantially as described.

4. The combination with a trolley-harp having its inner faces provided with recesses, of a shaft mounted in the side portions of said

harp and passing through said recesses, a trolley-wheel mounted on said shaft and provided with a hub having concave lateral faces and brushes having an opening therethrough for receiving said shaft and being adapted to rest 20 in said recesses and engage the concave lateral faces of said hub, substantially as described.

In testimony whereof I affix my signature in the presence of two witnesses.

WILLIAM A. HELLER.
